SWITCH

Charles H. Reynolds, Malden, Mass., assignor to
Albert and J. M. Anderson Manufacturing Com-
pany, South Boston, Mass., a corporation of
Massachusetts

Application August 10, 1931, Serial No. 556,142

2 Claims. (Cl. 200—169)

This invention relates to an electrical switch and more particularly to a disconnecting switch for use in high tension circuits.

In general the object of the invention is to provide a novel and improved construction of switch in which the switch blade is latched in circuit-closing position by novel and improved latching mechanism.

A further and more specific object of the invention is to provide a novel and improved construction of double throw switch having provision for latching the switch blade in either circuit-closing position and in which the latching mechanism is adapted for cooperation with the standard switch stick at present used in connection with the standard high tension disconnecting switches and in which the movement of the switch blade into and from circuit-closing position by means of the standard switch stick is accomplished with a minimum strain and wear upon the latching mechanism to the end that the switch may be used for long periods of time without attention and without replacement and also with a blade of minimum length and without diminishing the current carrying capacity of the blade.

With these objects in view, and such others as may hereinafter appear, the invention consists in the switches hereinafter described and particularly defined in the claims at the end of this specification.

In the drawing illustrating the preferred embodiment of the invention—

Fig. 1 is a plan, and Fig. 2, a side elevation of a double throw disconnecting switch embodying the present invention; and

Fig. 3 is a plan, and Figs. 4 and 5 are side elevations of modified forms of high tension disconnecting switches embodying the present invention.

Referring now to the drawing, in Figs. 1 and 2 I have illustrated a double throw high tension disconnecting switch embodying the present invention comprising essentially a movable member 10 pivoted at 12 and adapted to be thrown into one position to co-operate with one set of clips 14 to close one circuit, and which is also adapted to be thrown into the opposed position to co-operate with a second set of clips 16 to close another circuit.

As is generally recognized for high tension work, it is desirable and essential that provision be made for latching the movable member 10 of the switch in circuit-closing position, to prevent the heavy surge of current from opening the

switch and to prevent accidents which have heretofore occurred by reason of the shearing of the pivot pin for the movable member of the switch when the same is thus forced open under the surge of the heavy current.

The present invention has for its object to provide a high tension switch which is of minimum length and capable of being latched in its closed position without diminishing the current carrying capacity of the movable member or blades of the switch, and which can be located in a space of minimum length.

In accordance with the preferred embodiment of the invention, the movable member of the switch is provided with one, and preferably with two latching members 20, 22, which are herein shown as pivoted upon pins 23, 24 and located between the switch blades 25, 26 making up the movable member of the switch as in the manner illustrated in Figs. 1 and 2, wherein it will be seen that the latching members 20, 22, in the closed position of the blades 25, 26, are located between the pivot 12 and the clip 14 or 16 with which the blades are engaged.

The latching members 20, 22 are provided with hooked portions 27, 28, which are adapted to hook under catches 29, 30 upon the inside of the clips 14, 16.

The latching members 20, 22 are urged into operative or catch-engaging position by a compression spring 31 preferably in the shape of a coil disposed around one of the spacing sleeves 32 through which a retaining bolt 34 for holding the switch blades 25, 26 in operative relation is extended.

As herein shown the free ends of the coil spring 31 are received within recesses in the latch members 20, 22.

In order to operate the latch members 20, 22 to disengage them from the catches 27, 28, and also for the purpose of enabling the movable member 10 of the switch to be moved by the switch stick to disengage it from the clips 14, 16, each latch member 20, 22 is further provided with an eye 35 of a size sufficient to permit the insertion therein of the operative end of a standard switch hook or switch stick which is used in practice in unlatching and moving the blade of a high tension disconnecting switch. The eye 35 is located with relation to the movement of the latch from latching into unlatching position so that after the latch has been disengaged, the eye will have been moved toward the switch blade sufficiently to bring the operative portion of the switch stick or switch hook into direct contact or

bearing with the edge portion of the movable member 10 of the switch, and so that upon further movement of the movable member 10 under the push or pull of the switch stick accordingly as 5 the blade is being moved out of or into disengagement with the clips, the switch stick bears directly against the edge of the movable member 10 of the switch and all strain is relieved from the latching mechanism and taken directly upon 10 the movable member itself.

In this manner liability of rendering the latching mechanism inoperative is reduced to a minimum and the life of the switch is prolonged.

In order to control the movements of the 15 latching members 20, 22, as herein shown, each latching member is provided with a hole through which extends a contact pin 42 carried by the movable member 10 of the switch, so that each latching member is limited in its pivotal movement by the engagement of the opposite walls of the hole with the pin, as clearly illustrated in Figs. 1 and 2.

As illustrated in Figs. 3 and 4, a single latch member 22 is provided constructed in the manner 25 previously described and the second end of the spring 31 is received within a recess in a stationary lug 45 which is arranged to project above the blades to enable the switch stick to co-operate therewith when the stick is used in forcing the 30 movable member 10 of the switch into engagement with the clip 14.

In Fig. 5 I have illustrated a modified form of 35 single throw switch in which the lug 45 is pivoted to the switch blade and in which the movement of the lug 45 by the switch stick when closing the blade operates to increase the compression in the spring 31 and thereby render the latching of the blade by the latch 22 more positive and efficient.

From the description thus far, it will be observed that in accordance with the present invention 40 a high tension disconnecting switch is provided having a latching mechanism of a simple durable construction, in which the latching mechanism occupies a minimum space and may be manufactured economically, particularly inasmuch as the latches may be stamped out of plate.

While it is preferred to employ the duplicate 45 latching mechanisms on both a single and a double throw switch, nevertheless a single latch may be used as illustrated in Fig. 3.

In operation the operator hooks the switch stick through the eye 35 of the lower latch and is enabled to disengage the latch from its catch 50 during the initial movement of the latch into a position where the operative portion of the switch stick is brought into direct contact with the under edge of the switch member 10. The further movement of the switch stick bearing directly against the member 10 positively disengages the same from its clip and continued movement swings the switch member 10 past the vertical and into a position where the downward pull of the switch stick bearing directly against the same edge of the switch member operates to 55 positively pull the switch blade into engagement with the second set of clips. The movement of the spring as the switch blade is being disengaged, operates to increase the compression in the 60 spring so that the second latch member is rendered more active by the increase in compression in the spring to engage its catch when the blade is moved into the opposite circuit-closing 65 position.

Furthermore, it will be observed that the latching members are pivoted to the blades between the ends of the latter and at such a distance from the free ends of the blades that, in the closed position of the blades, the said latches are between the clips 14 or 16 and the pivot 12 for the blades. This construction enables the switch to be of minimum length and used in places where the space, in which the switch can be placed, is of limited length as, for instance, in 70 cells or housings in which high tension switches are usually located.

So also, it will be observed that the latching member 20 or 22 is provided with the eye 35 into which the switch stick is extended, and that the current carrying capacity of the blades 25, 26 is not diminished by the formation of the eye 35 in the blades. It will therefore be seen that by providing the latching members 20 or 22 with an eye 35 for the engagement of the switch stick and pivoting the latching member to the blades so that the latching member in the closed position of the switch is located between the free end of the blade and the pivoted or fixed end, a latched high tension switch of maximum current carrying capacity and of minimum length may be obtained.

While the preferred embodiment of the invention has been illustrated and described, it will be understood that the invention may be embodied in other forms within the scope of the following claims.

Having thus described the invention, what is claimed is:

1. A switch having, in combination, a movable 110 switch member pivoted at one end, a clip with which the free end of the movable member is engaged in its closed position, a catch on said clip, a latching member pivoted to the movable switch member and having its free end extended laterally beyond the side edge of the movable switch member and provided with a latch 115 co-operating with said catch and having means for engagement with a switch stick, said means being removed from the side edge of the movable switch member a distance sufficient to enable the projecting end of the latching member to be pushed toward the side edge of the movable switch member and effect disengagement of the latch from said catch and leave the movable 120 switch member free to be moved to open the switch by direct thrust of the switch stick in the same direction against the side edge of the movable switch member.

2. A switch having, in combination, a movable 130 switch blade pivoted at one end, a clip with which the free end of the said blade is engaged in its closed position, a catch on said clip, a latching lever pivoted to the said blade and having its free end projecting laterally beyond the 135 side edge of said blade and provided with a latch co-operating with said catch and having an eye for engagement with a switch stick, said eye being removed from the side edge of said blade a distance sufficient to enable the projecting end 140 of the latching lever to be pushed toward the side edge of the blade and release the latch from said catch and leave the switch blade free to be moved into its open position by direct thrust of the 145 switch stick in the same direction against the side edge of said blade.

CHARLES H. REYNOLDS.
